DESIGN FOR A TRAILER

Hilton B. Murray, New York, N. Y.

Application December 5, 1935, Serial No. 59,911

Term of patent 3½ years

To all whom it may concern:

Be it known that I, Hilton B. Murray, a citizen of the United States, residing at 246 Lexington Avenue, in New York city, in the county of New York and State of New York, have invented a new, original, and ornamental Design for a Trailer, of which the following is a specification, reference being had to the accompanying drawing, forming part thereof.

Figure 1 is a perspective view showing the front and side of my trailer with the flexible detachable side screen cover removed.

Figure 2 is a perspective view showing the rear and side of my trailer with the flexible detach-

able screen cover and flexible roll cover shown in a partly open position.

My trailer design consists of a series of narrow vertical panels around the lower side and end portions. In the upper portion the end and side screened sections are inclosed by flexible detachable side screen covers and a flexible roll cover on the curved front and rear end roof portions. The side opposite the side shown is similar in appearance.

I claim:

The ornamental design for a trailer, as shown and described.

HILTON B. MURRAY.
